CLAIM

The ornamental design for an organ bench, as shown and described.

DESCRIPTION

FIG. 1 is a front perspective view of an organ bench showing my new design;

FIG. 2 is a front elevational view thereof;

FIG. 3 is a left side elevational view, the right side being a mirror image thereof;

FIG. 4 is a top plan view thereof; and,

FIG. 5 is a top plan view thereof with the seat turned at a different angle.

FIG. 1

FIG. 2

FIG. 3

FIG. 4

FIG. 5
